UNITED STATES PATENT OFFICE

PHILIP A. KOEHRING, OF MILWAUKEE, WISCONSIN, ASSIGNOR TO KOEHRING COMPANY, OF MILWAUKEE, WISCONSIN, A CORPORATION

BOOM CONSTRUCTION FOR PAVING MACHINES

Application filed April 1, 1929. Serial No. 351,774.

Concrete mixers of the type now widely known as pavers, include distributing apparatus in the form of a boom and bucket mechanism. In the use of such distributing apparatus the bucket traverses the boom through the medium of a trolley which travels along the boom and from which the bucket is suspended. The trolley comprises rollers which move along flanges constituting a part of the boom construction. In the construction of a conventional paving machine the boom distributor is supported on the main mixing machine for movement vertically and to swing horizontally to provide proper distributing range, and horizontal and vertical axes, or pivot pins are used to enable these movements.

When a machine of the above type is working on horizontal grades the distributor operates excellently. But should the road or pavement incline transversely, the bucket maintains a vertical pendant position and causes the rollers constituting a part of the trolley to jam on one side, which effect has proved to be an operating disadvantage in many instances, not to mention the setting up of undue stresses in the hanger member supporting the bucket on the trolley.

The instant invention broadly contemplates the provision of a novel type of boom together with its mounting, which boom functions to maintain the bucket it supports in a condition of true suspension regardless of the position of the body of the paver with respect to the horizontal. This end is attained by mounting the boom on the body with a pivotal mounting comprising pivots in the three dimensions, this in lieu of the practice heretofore availed of a pivotally mounting the boom in only two dimensions as previously mentioned.

This invention accomplishes its object through the provision of a pivotal mounting for a boom which permits the boom to rock or tilt on an axis which is in alignment with the longitudinal dimension of the boom.

In carrying out my idea more in detail the inner end of the boom is provided with brackets for carrying a pin that adapts the boom for swinging in a vertical plane. This

pin in turn is mounted on another pin having suitable bearing in a pivoted plate, and this pin renders to the boom the capability of oscillating on an axis extending lengthwise with respect to the boom. The pivoted plate is pivotally mounted on the body of the machine and permits movement of the boom in a horizontal plane. Suitable instrumentalities are provided for controlling the turning actions of the boom in the vertical and horizontal planes while the bucket is permitted to control the swivelling action of the boom on its longitudinal axis.

It might be well to note at this point that a freely turning boom such as provided by this invention has the advantage of obviating any damage which might occur if the bucket were to strike against an obstacle during swinging of the boom in a horizontal plane, this advantage being attained due to the ability of the boom to turn on a longitudinal axis.

Particular objects and advantages of the invention arise in association with the provision of the mountings aforesaid, together with the means for controlling the turning movements of the boom. These will in part become apparent and in part be hereinafter stated as the description of the invention proceeds. For a full and more complete understanding thereof, reference may be had to the following description and accompanying drawings, wherein—

Figure 1 is a plan view of the inner end of the boom, bringing out the means employed for mounting the boom on the body of a paving machine.

Figure 2 is a view from the side of the apparatus shown in Figure 1, taken about on the line 2—2 of Figure 1, parts being shown in section and parts in elevation.

Figure 3 is an end view, somewhat diagrammatic, of a paving machine, bringing out the vertical disposition of the boom when the machine is disposed out of the horizontal.

Figure 4 is a detail view in perspective showing the bracket arrangement which is affixed to the boom proper.

Figure 5 is an end view of the bracket arrangement shown in Figure 4.

Figure 6 is a plan view bringing out the pin which extends longitudinally of the boom.

Figure 7 is a side view of the bracket arrangement which is affixed to the boom.

Figure 8 is a section taken on the line 8—8 of Figure 6, and

Figure 9 is a diagrammatic showing from the side, of the boom and bucket as applied to a paving machine.

While a preferred, specific embodiment of the invention is herein set forth, it is to be understood that I am not to be limited to the exact constructions illustrated and described, because various modifications of these details may be provided in putting the invention into practice within the purview of the appended claims.

Throughout the drawings and following description, like reference characters denote corresponding parts.

A paving machine is shown in Figures 3 and 9 and referred to generally by the reference character A. This machine is mounted on traction devices B which travel over the ground or the surface on which the machine operates. A boom C extends from the machine A, and intended for travel along this boom is a bucket D which receives concrete from the mixing apparatus in the machine A and distributes the same on the sub-grade to be paved.

The boom C is of a channel bar construction as clearly shown in Figures 1 and 4, and comprises channel bar members 1 and 2 which in turn are provided with the flanges 3 on which the trolley carrying the bucket operates.

A bracket 4 is affixed to the body of the paver A in any preferred manner such as by riveting the same thereto through the openings shown at 5. The bracket 4 is provided with a portion 6 which has an opening therethrough and constitutes the bearing for a segmental plate 7 which has a pivot member 8 extending through the opening in the portion 6. A nut and bolt arrangement shown at 9 serves to maintain engagement between the segmental plate 7 and the bracket 4.

The segmental plate 7 is provided with worm gear teeth as shown at 10 which cooperate with a worm 11 that is operated by any suitable instrumentalities such as shown at 12 to cause a turning of the boom in a horizontal plane. The member 7 is formed with a portion 13 having a horizontal bore 14. This portion 13 with its bore 14 constitutes a bearing for the pin member 15 which may be held in proper position in the bore 14 by a counterpin as shown at 16. The pin 15 is of the construction clearly shown in Figures 6 and 8 and includes a transverse opening 17 which constitutes a bearing for a pin 18. The pin 18 constitutes a pivotal axis for the bracket device shown at 19 that is affixed to the chan-

nel members 1 and 2 comprising the boom C. The bracket device 19 may be fastened to the boom members 1 and 2 in any preferred manner such as by rivets shown at 20.

The construction of the bracket device 19 is such that it accommodates the journal portion 13 of the segmental member 7, this formation of the bracket device 19 being clearly shown in Figure 5. The pin 15 is provided with the lubricating means shown at 21 for lubricating the bearing of the pin 18 in the opening 17.

From the foregoing, it is apparent that the parts 6 and 8 provide for a swinging of the boom in a horizontal plane while the pin 18 provides for the swinging in a vertical plane. The pin 15 together with its journal 13 affords the tilting of the boom about an axis co-extensive with the longitudinal dimension of the road in which the paver rests in accordance with the objects of this invention. This tilting action of the boom is limited only by the relation between the extremities of the pin 18 and segmental member 7.

Reference is made particularly to Figure 3, in which the paving machine A is shown inclined side-wise but the boom C has by automatic or self-adjustment assumed or maintained a true vertical position along with the suspended bucket D. The view is exaggerated but depicts the position of the boom distributor in having a proper free action though the machine carrying it is laterally inclined.

Having thus described my invention, what I claim as new and desire to secure by Letters Patent of the United States, is

1. A boom construction of the class described, comprising, in combination, a boom, a bracket device affixed to the boom, a pivotal mounting for the bracket device, a pivotal mounting for the first named pivotal mounting, and a third rotatable mounting carrying the first two pivotal mountings, and a distributing bucket disposed to operate on the boom.

2. A boom construction of the class described, comprising, in combination, a boom, a bracket device affixed to the boom, a pivotal mounting for the bracket device, a pivotal mounting for the first named pivotal mounting, a third rotatable mounting carrying the first two pivotal mountings, and means for controlling turning operations of the boom on its various axes.

3. A boom construction of the class described, comprising, in combination, a boom, a bracket device affixed to the boom, a pivotal mounting for the bracket device, a pivotal mounting for the first named pivotal mounting, a third rotatable mounting carrying the first two pivotal mountings, and means for controlling turning operations of the boom on its various axes, said means including manually operable devices for controlling

turning operations in the vertical and horizontal planes and a bucket for controlling the swivelling actions of the boom on a longitudinal axis.

5. In a paving machine of the class described, a boom, inflexible drive means for swinging said boom in a plane substantially parallel to the road on which the machine rests, and a universal joint providing for 10 movement of the boom about angularly related axes.

5. In a paving machine of the class described, a boom mounted on an axis extending longitudinally of the machine, and inflexible 15 drive means for swinging said boom in a plane substantially parallel to the road on which the machine rests.

6. In a paving machine of the class described, a boom, a machine frame, a member 20 mounted on said frame for pivotal movement in one plane only, said frame having means for imparting movement to said member, and a connection between said member and said boom, said connection providing for movement of said boom about an axis extending longitudinally of the frame.

7. In a paving machine of the class described, a boom, a machine frame, means providing a universal joint between the boom 30 and the frame, said means including a member mounted on the frame for pivotal movement in a plane parallel to the road over which the machine moves, and a pivotal connection between the boom and said member 35 providing for movement of said boom about an axis extending longitudinally of the frame.

8. In a paving machine of the class described, a boom, a frame having a bracket 40 provided with a pivot opening substantially normal to the road over which the machine moves, a member having a pin disposed in said opening, means for causing pivotal movement of said member in said opening, and a bracket on the boom and connected with said member for pivotal movement relative thereto about an axis longitudinally of the frame.

9. In a paving machine of the class described, a boom, a frame, a toothed member 50 pivoted to the frame for movement in a plane parallel to the road on which the machine rests, threaded means mounted on the frame, and coacting with the toothed member to move the latter, and a pivotal connection between the boom and member providing for movement of the boom about an axis longitudinally of the frame.

10. In a paving machine of the class described, a boom, a frame, a toothed member 60 pivoted to the frame for movement in a plane parallel to the road on which the machine rests, threaded means mounted on the frame and coacting with the toothed member to move the latter, and a pivotal connection be-

tween the boom and member providing for movement of the boom about an axis longitudinally of the frame, said member having a pivot opening and said boom having a pin pivotally mounted in said opening.

11. In a paving machine of the class described, a boom, a frame, a gear sector pivoted to the frame for movement in a plane parallel to the road on which the machine rests, threaded means mounted on the frame and coacting with the gear sector to move the latter, and a pivotal connection between the boom and sector providing for movement of the boom about an axis longitudinally of the frame.

12. In a paving machine of the class described, a boom having a bracket provided with a pin mounted on the bracket for pivotal movement relative thereto in a plane normal to the road on which the machine rests, a machine frame, a bracket on the frame, and instrumentalities mounted on said bracket for moving the boom in a plane parallel to the road, said instrumentalities including a pivot opening extending longitudinally of the frame, said pin being mounted in said opening, whereby said boom is movable in a plurality of angularly related planes.

13. In a paving machine of the class described, a boom having a bracket provided with a pin mounted on the bracket for pivotal movement relative thereto in a plane normal to the road on which the machine rests, a machine frame, a bracket on the frame, and instrumentalities mounted on said bracket for moving the boom in a plane parallel to the road, said instrumentalities including a pivot opening extending longitudinally of the frame, said pin being mounted in said opening, whereby said boom is movable in a plurality of angularly related planes, said instrumentalities including further gear and worm members.

In testimony whereof I affix my signature. 110
PHILIP A. KOEHRING.
